UNITED STATES PATENT OFFICE.

NICOLS LINDBERGH, OF NELSON, MINNESOTA, ASSIGNOR OF ONE-HALF TO
JACOB P. LARSON, OF SAME PLACE.

BOTTLE-STOPPER.

SPECIFICATION forming part of Letters Patent No. 606,290, dated June 28, 1898.

Application filed November 9, 1896. Serial No. 611,537. (No model.)

To all whom it may concern:

Be it known that I, NICOLS LINDBERGH, a citizen of the United States, residing at Nelson, in the county of Douglas and State of Minnesota, have invented certain new and useful Improvements in Bottle-Stoppers; and I do hereby declare the following to be a full, clear, and exact description of the invention, such as will enable others skilled in the art to 10 which it appertains to make and use the same.

This invention has reference to a bottle-stopper that is adapted to be placed within the neck of a bottle and which serves to prevent the bottle from being refilled.

15 The invention consists in the features of construction hereinafter fully described and claimed.

In the accompanying drawings, forming a part of this specification, Figure 1 is a central 20 vertical section of a device constructed in accordance with this invention and situated within the neck of a bottle. Fig. 2 is a similar view showing the position of the parts when the bottle is turned upon its side.

25 Referring now to said drawings, 1 indicates the neck of the bottle, and 2 the cork or stopper. This cork or stopper is provided with a packing-ring, preferably of cork, and is provided with a central opening 3. Situated 30 within this opening 3 is a tube or passage 4, having a flange 5 at its lower end situated against the lower end of the packing-ring or cork, while its upper end portion flares outwardly, as shown at 6, and extends a little 35 distance above the cork 2. Beyond the upper end of the straight portion of the tube or

passage 4 is a perforated plate 7, provided with an uprising stem 8. A valve 9 is carried by said stem and serves to close the openings in the plate 7. The upper end of the stem is 40 preferably cup-shaped, as shown at 10, to receive the ball 11, that is rigidly fastened thereto by cement, sealing-wax, or the like. This ball 11 can be of glass and serves to prevent the insertion of a sharp instrument to 45 reach the valve.

It will be seen from the foregoing description that when a stopper of this construction is situated within the neck of a bottle it will readily allow the contents to pass out therefrom by raising of the outwardly-opening valve 7, while said valve effectually prevents the entrance of liquid into the bottle.

Having thus described my invention, what I claim as new, and desire to secure by Letters 55 Patent, is—

The combination with a packing-ring or stopper having a central opening, of a tube or passage situated within said opening and having a flange at one end resting against the 60 end of said stopper or packing-ring, an apertured plate at the other end of said tube or passage, a stem extending from said plate and provided with a head, a valve upon said stem and a flaring mouth for said tube or passage. 65

In testimony whereof I have signed this specification in the presence of two subscribing witnesses.

NICOLS LINDBERGH.
